INSULATION

Application filed November 7, 1925. Serial No. 67,517.

My invention relates to an insulation particularly adapted for insulating walls, partitions, safe and vault walls and the like.

The invention will be described in connection with a safe or cabinet, but it is to be understood that the invention has a broader application and may be used wherever it is desired to protect any part against high temperatures for a limited period, such as when 10 a building burns.

Ordinarily, when a safe is insulated with the usual forms of dry insulation the amount of heat transmitted and the consequent temperatures of the interior of the cabinet depends, as one factor, upon the conductivity of the insulating material, and it will be obvious that, this conductivity remaining substantially constant, the interior temperature of the safe or cabinet may rise to a dangerous point if the safe is subjected to the intense heat of a fire for a protracted period.

Various expedients have been resorted to for the purpose of retarding the passage of heat into the interior of a cabinet so that the 25 contents thereof might be adequately protected. It is well known that, if water can be held in the interior of the safe walls, the temperature of the interior of the safe will be maintained at a much lower temperature 30 than if dry insulation be provided; this for the reason that the latent heat of vaporization of water is very high and much of the heat transmitted through the safe walls is used up in vaporizing the water therein contained. The employment of water in open 35 containers or the like is unsatisfactory for the reason that the water in time evaporates and the function intended will therefore not be performed. In safes, at the present time, 40 so called "wet" insulation is often used. Such insulation usually comprises a concrete-like matrix soaked or wet with free water and this water often corrodes the safe walls, or drips out or evaporates so that it is unreliable as a safe insulation.

Various means have been employed for utilizing the so called water of crystallization of various salts or hydrates, of which there are many, alum being mentioned as one of 50 the more prominent. There are many other

salts or hydrates which may be advantageously employed, all efflorescing or giving up all or a part of their water of crystallization at temperatures at or below the maximum temperature desired to be maintained in the interior of a safe. Some available materials are deliquescent, with the consequence that when such materials are employed, the interior insulation may become wet and the safe walls and lining may be unduly corroded. Again, some salts which otherwise would be available effloresce at ordinary temperatures and for that reason are not suitable, since their function would be impaired in the course of time. Again, some water carriers may react with various bodies in which they would ordinarily be held in a safe insulation, and their function of providing water or moisture at the time of a fire would thus be materially impaired.

With all of the above difficulties and others in mind, it is the principal object of my invention to provide a thoroughly practical and reliable insulation for safes, vaults, walls, fire doors, partitions and the like, so constructed 75 that in case of a fire moisture will be given up in sufficient quantities and at the proper rate, so as to adequately protect documents and the like, protected by my insulation.

It is a more specific object to provide an insulation of the character indicated, in which the moisture carrying media are substantially uniformly distributed and so held and embodied as to yield their moisture in an effective practical manner.

It is still another object to provide means whereby many efflorescent salts and the like may be employed in insulations of the character noted and which will maintain their efficiency unimpaired for an indefinite period. 90 It is a still more specific object to provide an insulation carrying combined water, which insulation may be dried to a constant weight and will remain dry without affecting the combined water.

Other objects will be apparent as the specification proceeds.

Briefly stated, in the preferred form of the invention I employ water carriers preferably in the form of hydrates or salts, such as alum 100

or the like, which hydrates are preferably in lumps or crystals, which may be held or supported in a suitable matrix, such as gypsum or plaster of Paris. In order to prevent any 5 efflorescence at ordinary temperatures and to prevent chemical reactions being set up between the particular carriers employed and surrounding bodies, I preferably coat all or some of the lumps of alum or other material 10 employed with a suitable protecting envelope or covering. This covering should be substantially impervious to moisture at ordinary temperatures, but should be readily frangible at the higher temperatures at which it is desired to have the carriers give up their water. 15 This envelope may be in the form of a coating of paraffin, or the coating may be formed of other material, for example, shellac. The particular coating to be employed will depend 20 somewhat upon the particular hydrate or other water carrier employed and upon the matrix or body by which it is carried. When heat is transmitted to the protected bodies of alum or the like, the protecting envelope or 25 coating is readily melted or broken, and the water of crystallization given up and vaporized, with the employment of relatively great quantities of heat in so doing. If the particular matrix carrying the protected bodies be 30 porous, and I prefer to employ a porous matrix, the steam or vapor generated when the insulation is subjected to high temperatures passes through the porous matrix, and upon reaching the cooler parts thereof again 35 condenses, so as to substantially moisten the matrix, and this condensed vapor must again be vaporized before the transmitted heat passes through the blanket of moisture thus formed. Obviously, then, it is not only the 40 original water of crystallization contained in the hydrate which acts as the protecting blanket or shield, but this water, when vaporized and again condensed on the cooler parts of the matrix serves as a further or constantly 45 advancing blanket, which takes up transmitted heat as it penetrates deeper into the insulation. As the water of crystallization is given up, the lumps or crystals decrease in size, thus leaving voids or air pockets in the 50 original matrix, which pockets themselves serve as efficient insulators against further transmission of heat.

In the drawings which show, for illustrative purposes only, a preferred form of the 55 invention—

Fig. 1 is an isometric view of a cabinet or safe having a section of one wall broken out so as to illustrate features of the invention;

Fig. 2 is an enlarged fragmentary section of one corner of the cabinet shown in Fig. 1;

Fig. 3 is an enlarged fragmentary portion of a section of insulation illustrating features of the invention;

Fig. 4 is a partially diagrammatic view of

a lump or crystal of a hydrate partially coated with a protective covering.

In said drawings 5 indicates generally any suitable type of safe, vault or cabinet having an outer wall 6 and an inner wall 7, which, if desired, may be of sheet metal. The walls of the lateral sides, top and bottom, as well as of the door, are preferably spaced apart so as to enclose insulation, as hereinafter described.

8 indicates an insulating body which, in the preferred form, is itself a good insulator and is of relatively porous texture. In the form shown I employ plaster of Paris to form the main body or matrix in the section 8. The matrix is provided, preferably uniformly distributed throughout, with water carriers, preferably in the form of lumps or crystals of efflorescent salts, such as alum. These lumps are designated 9—9 in the drawings. Each lump is preferably coated or enclosed in a suitable water impervious envelope or jacket 10, such as paraffin, so as to protect the various lumps or water carriers against the loss of moisture and also against the possibility of the undue absorption of moisture in case a deliquescent material should be employed. This protecting coating or envelope likewise protects and ensures against any chemical action being set up between the particular carrier employed and any surrounding body. Before use the matrix is preferably dried to a substantially constant weight so there is substantially no free or uncombined moisture present, and when used in a safe for example there will be no danger of corrosion or damage to the walls or contents of the safe. Obviously, the insulation 8 may be reinforced, if desired, with any suitable type or reinforcement, such as wire netting or the like, to give added mechanical strength, if this be found necessary.

Now the insulation as shown particularly in Figure 3, if desired, may be employed alone and without other insulation. However, in safe construction I prefer to employ other and lighter insulation outside of the insulation 8, so as to retard the transmission of heat to the insulation 8. In the form shown I interpose a layer 11 of suitable material, such as asbestos insulation, kieselguhr, or other form of dry heat insulation. It is preferred, however, to make the outer or shielding insulation 11 of substantial body and to secure the inner insulating sections 8 thereto in any suitable manner, so that the two layers of insulation may be handled and applied as a unit. The total insulation or any part thereof obviously may be sectional in structure or be a monolithic casting. As above indicated, all the walls of the safe, as well as the door, are preferably provided with the insulation as above described.

Now if a fire occurs, the heat will be transmitted quite slowly, depending upon the character of the insulation 11 employed and

the thickness thereof, as well as upon the outside and inside temperatures. The heat will be transmitted also quite slowly through the main body or matrix 8 of the inner insulation. 5 As soon as the temperature at the insulation 8 rises above a predetermined point, which varies with the character of the water carriers 9 employed therein, much of the heat will be utilized or absorbed in vaporizing the water 10 which is given up by the water carriers 9—9 distributed throughout the block 8. This vapor will pass through the porous block 8 and, upon reaching the cooler interior portions thereof, will again condense. Obviously, the temperature in the block 8 may rise 15 only slightly higher than the boiling point of water so long as there is any unvaporized water present. As soon as all of the water of crystallization is given up by the crystals in 20 the outermost layers of the block 8, the temperature further inward in the block rises and the moisture which has previously condensed on the interior portions is again vaporized, thus slowing up the transmission of heat to 25 the interior of the cabinet, which ultimately is the location to be protected. The same action takes place completely through the block 8. As shown particularly in Fig. 2 in an exaggerated fashion, perhaps, the inner lining 30 plates in the safe may be arranged so as to not fit tightly, or the inner wall may be otherwise vented, thus permitting some vapors to reach the inside of the cabinet, to prevent undue drying out or charring of documents in 35 the cabinet should the temperature eventually rise sufficiently for that to occur.

With the heat being transmitted relatively slowly, it will be seen that it will take a relatively great length of time to vaporize all of 40 the available water, and the interior of the safe will thus be protected. Manifestly, the insulation 8 and 11 may be made as thick as desired, and the quantity of available water may be varied as desired, so that a safe of any 45 desired characteristics, that is, one which will withstand high temperatures for any desired length of time, may be constructed.

I consider the enclosing of the water carriers in protecting coatings or coverings as 50 of the greatest importance, in that they will remain intact and ready for service for an indefinite length of time. Again, no appreciable amount of moisture will be given up 55 by the carriers which are thus protected, and if the insulation be otherwise put in dry, there need be no fear of corrosion of the walls of the safe nor of injury to articles within the safe due to moisture from the insulation.

60 While the invention has been described in great detail and one specific form illustrated, I do not wish to be confined to that form, since the invention has very wide application and may be embodied in various form and various materials used, all coming within the

scope of the invention as defined in the appended claims.

I claim:

1. An insulation construction including a supporting body, particles of salts containing water of crystallization supported by said body, said particles being substantially individually enclosed in frangible, impervious coating envelopes, whereby said coating envelopes may be ruptured and water vapors given off upon subjecting said insulation construction to relatively high temperatures. 70

2. In the combination defined in claim 1, said frangible, impervious coating envelopes being formed of paraffin. 75

3. An insulation construction including salts containing water of crystallization enclosed in envelopes of paraffin and imbedded in a matrix of plaster of Paris. 80

4. An insulation construction including particles of alum enclosed in envelopes of paraffin and imbedded in a matrix of plaster of Paris. 85

5. An insulation construction including a supporting matrix of substantially dry material and particles of salt containing water of crystallization enclosed substantially individually in impervious, frangible coating envelopes, said coated particles being embedded in and held by said supporting matrix. 90

6. An insulation construction including a layer of insulation having secured thereto a matrix of porous material, said matrix carrying salts containing water of crystallization, said salts being enclosed in impervious, frangible envelopes. 95

7. An insulation construction including a layer of heat insulation, a matrix of plaster of Paris secured to said layer of insulation, said matrix having imbedded therein salts containing water of crystallization, said salts being enclosed in envelopes of paraffin. 100
